ADJUSTABLE FUR STRETCHER

Andrew Lawrence, Cle Elum, Wash.

Application December 28, 1936, Serial No. 117,987

7 Claims. (Cl. 149—21)

My invention relates generally to means for stretching fur skins and the like, and particularly to a fur stretcher adapted to be made in different sizes, and an important object of my invention is to provide devices of this class which are adjustable to accommodate different intermediate sizes of furs, within the range, for which the stretcher is constructed.

Another important object of my invention is to provide a fur stretcher of the character indicated which is efficient and inexpensive, and which does not require trained skill for its application and operation.

Other important objects of my invention will be apparent from a reading of the following description taken in connection with the drawings, wherein for purposes of illustration I have shown a preferred embodiment of my invention.

In the drawings:

20 Figure 1 is a general side elevational view of the embodiment of my invention.

Figure 2 is an edge elevational view of the upper part of Figure 1.

Figure 3 is a horizontal sectional view taken 25 through the lower part of the embodiment and looking downwardly.

Figure 4 is a view generally similar to Figure 1 of the drawings of another embodiment of my invention.

30 Figure 5 is an edge elevational view of the upper part of Figure 4.

Figure 6 is a horizontal sectional view taken through the lower part of Figure 4 and looking downwardly.

35 Figure 7 is a transverse vertical sectional view taken through the lower part of Figure 4.

Referring in detail to the drawings, the numerals 5 and 6, in Figures 1, 2 and 3, refer respectively to the two longitudinal members which 40 compose the body of the stretcher at the upper end of each of which has a cut away portion 7, 8, respectively, defining the respective shoulders 9 and 10. Pivoted as indicated by the numerals 11 and 12 to the resultant reduced portions are the 45 curved and tapered fingers 13, 14 which have squared lower ends 15, 16 which are normally spaced from the corresponding shoulders 9, 10, which shoulders act as stops when the fingers are in extreme pivoted positions. The fingers 13, 14 normally lean in toward each other as illustrated in Figure 1 of the drawings.

The upper ends of the longitudinal members 5 and 6 are spaced and connected by means of the tensioning spring which is generally designated 55 and which has the general inverted V-

shape shown in Fig. 1, the apex of which includes the coil or convolution 18 which supplies the spring tension. The opposite arms 19, 20 have ends embedded and anchored in the laterally inward edges of the longitudinal members as 5 shown.

The lower end of the longitudinal member 5 has fastened thereto by means of the screw or the like 21, one end of the bottom bar 22, which bar is provided in its opposite end with a longitudinal slot 23 which receives the tightening bolt 24 which is anchored as indicated by the numeral 25 in the lower end of the longitudinal member 6 and extends through the slot 23 beyond which it is provided with the washer 26 at the thumb 15 nut 27.

An intermediate point of the bottom bar 20 has fastened thereto as indicated by the numeral 28 the lower end of a coiled spring 29 whose upper end has a hook or eye 30 which is engageable with one end of the fur skin 31 for stretching the fur in one direction.

In operating the device of the invention the fur skin is made into the usual envelope and is then placed on the device of the invention with 25 the longitudinal members 5 and 6 drawn toward each other until the pelt has been drawn down along these members to the proper length and hooked on the stretcher spring 29, whereupon the side portions of the pelt are nailed or tacked 30 to the longitudinal members 5 and 6. When this has been accomplished, the sections 5 and 6 are forced away from each other until a sufficient stretch of the pelt has been achieved, whereat the thumb screw 27 is turned up to clamp the 35 sections in their new positions.

The spring 17 pushes the upper ends of the sections 5 and 6 and their fingers or heads 13, 14 sufficiently away from each other into a spread relationship so that the skin or pelt is adequately 40 stretched throughout its length. It is obvious that the spring 17 may be arranged in cooperation with the bottom bar 22 and its clamping arrangement so that skins of different sizes within the range of the stretcher described may be 45 accommodated.

Referring specifically to the embodiment of the invention which is shown in Figures 4, 5, 6 and 7 of the drawings, it will be observed that this comprises a frame composed of side longitudinal 50 members 5' and 6' having at their upper ends heads 13' and 14' which are pivoted like the heads 13 and 14 on pivots 11' and 12'.

Intermediate portions of the longitudinal side members are cut in as indicated by the numerals 55

32 and 33 to define shoulders 34 and 35, the cut out portions and the shoulders forming seats for the generally L-shaped brackets 36 and 37 which have ears attached to the opposite sides of these 5 longitudinal members and bifurcated portions through which pivots 38 and 39 pass. On these pivots are pivoted the outer ends of links 40, 41 which are pivotally connected together at their inner ends by the pivot 42 which pivots the upper 10 end of a rod 43 to the links.

The rod 43 has an enlarged rectangular portion 44 whose lower end portion 45 is reduced and provided in one side with vertically spaced notches 47 with which engages a spring detent 15 46 which is fastened as indicated by the numeral 48 to the bottom of one side of the bottom adjusting bar 22' which corresponds to the bottom adjusting bar 22 in the first described embodiment of the invention. The adjusting bar 20 22' has therein a longitudinal slot 49 in which the reduced portion 45 of the bar 44 slides both vertically and longitudinally relative to the bar 22', and this bar is further provided with a slot 25 23' in which works the bolt 24' which has thereon the wing nut 27' urging the washer 26' into locking engagement with the bar 22'. An opposite end portion of the bar 22' is secured by fastening means 21' to the longitudinal member 5'.

To an intermediate part of the bar 22 is fastened a stretching spring 29' similar to the spring 29 in the first described embodiment and which is provided with a hook or eye 30' for engaging the skin 31'.

The first described embodiment of the invention is more suited for use for stretching muskrat, opossum and the like skins, while the second described embodiment is more suited to the stretching of mink, marten, fox, and the like having a fixed stretched adjustment. In the 35 case of the embodiment shown in Figure 4 the shoulder spreading mechanism comprises the links 40 and 41, whereas in the first described embodiment the shoulder spreading arrangement is the spring 17.

45 Although I have shown and described herein preferred embodiments of my invention, it is to be definitely understood that I do not desire to limit the application of the invention thereto, and any change or changes may be made in the structure and arrangement of the parts, within 50 the spirit of the invention and the scope of the subjoined claims.

What is claimed is:

1. A fur skin stretcher comprising a pair of 55 elongated substantially rigid side members arranged in substantial parallelism, a tip pivoted on one end of each side member on an axis disposed at right angles thereto, a stop adjacent the pivot adapted to be engaged by the respective tip to limit laterally inward leaning of the tip toward the opposed tip, and spacing means adjustably spacing the opposite ends of said side members.

2. A fur skin stretcher comprising a pair of 60 elongated substantially rigid side members arranged in substantial parallelism, a tip pivoted on one end of each side member on an axis disposed at right angles thereto, a stop adjacent the pivot adapted to be engaged by the respective tip to limit laterally inward leaning of the tip toward the opposed tip, and spacing means 65 adjustably spacing the opposite ends of said side members, expanding means between and attached to the first mentioned ends of the side members.

75 3. A fur skin stretcher comprising a pair of

elongated substantially rigid side members arranged in substantial parallelism, a tip pivoted on one end of each side member on an axis disposed at right angles thereto, a stop adjacent the pivot adapted to be engaged by the respective 5 tip to limit laterally inward leaning of the tip toward the opposed tip, and spacing means adjustably spacing the opposite ends of said side members, expanding means between and attached to the first mentioned ends of the side members, said expanding means comprising a pair of pivotally connected links having their outer ends pivoted to the said first mentioned ends of the side members, and operating means for spreading and contracting said links.

4. A fur skin stretcher comprising a pair of 10 elongated substantially rigid side members arranged in substantial parallelism, a tip pivoted on one end of each side member on an axis disposed at right angles thereto, a stop adjacent the pivot adapted to be engaged by the respective 15 tip to limit laterally inward leaning of the tip toward the opposed tip, and spacing means adjustably spacing the opposite ends of said side members, expanding means between and attached to the first mentioned ends of the side members, said expanding means comprising an expanding spring having opposed ends fastened to and between the first mentioned ends of the side members.

5. A fur skin stretcher comprising a pair of 20 elongated substantially rigid side members arranged in substantial parallelism, a tip pivoted on one end of each side member on an axis disposed at right angles thereto, a stop adjacent the pivot adapted to be engaged by the respective 25 tip to limit laterally inward leaning of the tip toward the opposed tip, and spacing means adjustably spacing the opposite ends of said side members, expanding means between and attached to the first mentioned ends of the side members, said expanding means comprising a pair of pivotally connected links having their outer ends pivoted to the said first mentioned ends of the side members, and operating means for spreading and contracting said links, said operating 30 means comprising a longitudinally movable rod pivotally connected to said links substantially on the axis of said pivot, said spacing means being formed with an opening slidably receiving said rod.

6. A fur skin stretcher comprising a pair of 35 elongated substantially rigid side members arranged in substantial parallelism, a tip pivoted on one end of each side member on an axis disposed at right angles thereto, a stop adjacent the pivot adapted to be engaged by the respective tip to limit laterally inward leaning of the tip toward the opposed tip, and spacing means 40 adjustably spacing the opposite ends of said side members, expanding means between and attached to the first mentioned ends of the side members, said expanding means comprising a pair of pivotally connected links having their outer ends pivoted to the said first mentioned ends of the side members, and operating means for spreading and contracting said links, said operating 45 means comprising a longitudinally movable rod pivotally connected to said links substantially on the axis of said pivot, said spacing means being formed with an opening slidably receiving said rod, said spacing means being provided with a spring detent for releasably engaging depressions formed in said rod to hold said rod in an adjusted position.

7. A fur skin stretcher comprising a pair of elongated substantially rigid side members arranged in substantial parallelism, a tip pivoted on one end of each side member on an axis disposed at right angles thereto, a stop adjacent the pivot adapted to be engaged by the respective tip to limit laterally inward leaning of the tip toward the opposed tip, and spacing means ad-

justably spacing the opposite ends of said side members, and a stretching spring attached to said spacing means between said side members, said stretching spring having an element engageable with the adjacent end of the skin for stretching the skin toward said spacing means. 5

ANDREW LAWRENCE.
